SINGLE RAIL GRINDER

Henry H. Talboys and Helmer E. Erickson, Milwaukee, Wis., assignors to Nordberg Manufacturing Co., Milwaukee, Wis., a corporation of Wisconsin

Application January 7, 1942, Serial No. 425,846

23 Claims.

(Cl. 51—178)

The invention relates to an improvement in track working tools and has for one purpose the provision of a track working tool, for example a rail grinder, which is mounted on and movable along a single rail of a track.

Another purpose is the provision of improved drive means for a track working member, such for example as a grinder.

Another purpose is the provision of improved means for mounting the power plant of track working equipment.

Another purpose is the provision of improved means for controlling and adjusting the movement of a track working member toward and away from the rail or rails of a track.

Another purpose is the provision of improved means for holding a track working frame in position on a single rail, for example when it is out of use or in intervals between use.

Other purposes will appear from time to time in the course of the specification and claims.

The invention is illustrated more or less diagrammatically in the accompanying drawings wherein:

Fig. 1 is a side elevation;

Fig. 2 is a plan view;

Fig. 3 is an end view, with parts broken away and parts omitted;

Fig. 4 is a section on the line 4—4 of Fig. 1;
Fig. 5 is a detail;

Fig. 6 is a vertical axial section on an enlarged scale through the grinding member and the drive therefor, on the line 6—6 of Fig. 2;

Fig. 7 is a section on the line 7—7 of Fig. 6;
Fig. 8 is a section on the line 8—8 of Fig. 1;

Fig. 9 is a section on an enlarged scale taken on the line 9—9 of Fig. 8;

Fig. 10 is a section on the line 10—10 of Fig. 9;
Fig. 11 is a section on the line 11—11 of Fig. 6;

Fig. 12 is a section on the line 12—12 of Fig. 6;
and

Fig. 13 is a detail.

Like parts are indicated by like symbols throughout the specification and drawings.

Referring to the drawings, 1 generally indicates a rail of a track, the rail being mounted for example on any suitable ties 2. "A" generally indicates a track working main frame of a grinder, which may include for example two horizontal longitudinally extending frame members 3, having a pair of cross members 4 at one end, and cross members 5 at the opposite end, and a plurality of cross members 6 adjacent the center of the frame thus formed. Double flanged supporting wheels 7, 8 are provided at

the opposite ends of the main frame A. One of the wheels is shown as journaled in the downwardly extending ears 9 mounted on the cross members 4. The opposite roller is journaled on ears 10 extending downwardly from the transverse frame members 5 at the opposite end of the frame. The ears 9, for example, may be mounted on a plate 11, and 12 indicates height adjusting shims.

10 At one end of the frame are a pair of upright frame members 13, 13, and intermediate the middle of the frame are a second pair of uprights 14, 14. The tops of the members 13 are connected by a transverse frame member 15.

15 Each pair of members 13 and 14 are connected by a handlebar 16, the ends of the handlebar extending outwardly beyond the frame, as at 17. On the tops of the inner end of the handlebars 16 are a pair of transversely extending frame members 18, shown for example at the middle of the top of Fig. 1. Extending longitudinally horizontally along the frame from one of the members 18 is an axially disposed handlebar 19, supported at the opposite end of the frame by

20 triangle members 20 and having an outwardly extending end portion 21. The members 14, 14 are also connected intermediate their ends by a transverse frame angle member 22, to which are welded a pair of spaced abutment blocks 23.

25 The intermediate frame members 6, 6 are also connected by a pair of spaced longitudinally extending frame members 24. In the space defined by the frame members 6 and 24, as shown in Fig. 8, is welded or otherwise secured a ring 30, 25, which serves as a species of housing or guard member for the below described grinding element. It will be observed that it is upwardly curved or cut away at one side, as at 26.

30 Mounted on the abutment blocks 23 of the cross members 22 and on the bottom intermediate frame members 24 is a housing or support generally indicated as B, which includes a half round portion 30, which is completed at the top by a ring portion 31, the two being held together by bolts 32 and any suitable nuts 33. Within the structure thus formed is any suitable ball race structure generally indicated as 34. A similar ball race 35 is mounted toward the bottom of the member 30, it being defined between the lower portion of the member 30 and the split half ring portion 36. At the bottom of the member 30 is a generally conic half skirt 37. The skirt portion 37 is provided with a pair of flanges 38, which may be bolted or otherwise secured to the members 24. The upper portion

45

50

55

of the member 30 is secured to the angle member 22, for example by any suitable bolts 40. Also secured to an upper portion of the member 30 is a plate 41, which may be held in position for example by spacing washers 42 on the bolts 32. The plate 41 carries a vertical rod 43, the upper end of which is seated in a socket 44 on the bottom of the single handlebar 19.

Mounted for rotation within the ball bearing races 34 and 35 is an outer sleeve 45, and a generally conic frictional driven member 46. It moves unitarily with the sleeve 45, being secured thereto in any suitable way. Keyed within the sleeve 45, as by the key 47, is a splined sleeve 48. It is positioned, for example, by an inner sleeve or hollow tube 49. Within the splined sleeve 48 is the grinder shaft 50, provided with grooves 51 to receive the teeth of the splined sleeve 48. Thus, it will be understood that the grinder shaft 50 may move vertically in relation to the outer sleeve 45, and the parts which move unitarily with the outer sleeve 45, but that it may be rotated in response to rotation of the outer sleeve 45. Mounted at the lower end of the grinder shaft 50 is a hub 52, which abuts against a bottom enlargement 53 of the shaft 50 and which may be held in relation thereto for example by the screw 54. The screw 54 is provided with a head 55, which serves to clamp the inner or upper plate 56 in relation to the hub 52 and the shaft 50. 57 is the grinding member proper, herein shown as a hollow ring extending downwardly from the plate 56, and connected thereto in any suitable manner. If desired, a yielding skirt 58 may be employed to prevent the access of dust to the shaft 50, the skirt being mounted in any suitable fashion, and being longitudinally extensive, as by being provided with folds.

The shaft 50 is provided with a reduced portion 60, which receives the inner race of the third ball bearing assembly, generally indicated as 61. 62 is a locking nut to hold the shaft and the inner race against relative movement.

The outer race 63 is supported within a sleeve 64, which in turn is connected to a tube 65, which is screw threaded as at 66 to mesh with corresponding threads of the interior of a sleeve 67 integral with or secured to the enlarged hub 68 of the hand control wheel 69. The hub 68 rests upon the ring 70, fixed between the transverse members 18. It will thus be understood that rotation of the wheel 69 will raise and lower the tube 65 and the sleeve 64, and thus raise and lower the grinder shaft 50, while permitting it to rotate in unison with the hollow shaft 45. Any suitable cover plate 71 may be employed for the hub of the wheel 69.

Screw threaded to the bottom of the sleeve 64 is a split locknut 75, which maintains the ball bearing assembly 61 in place in relation to the sleeve 64. The split nut 75 is surrounded by an open ring 76, the ears 77 of which straddle the vertical rod 43 and are bolted together as by the bolt 78, with spacers 79 welded if desired on the ears 77.

80 is a spring compressed between the fixed ring 70 and the split ring 75, the spring tending normally to urge the grinder shaft 50, with the grinder element 57 thereof, downwardly toward the rail.

When the wheel 69 is rotated in one direction, it raises the sleeve 65, and with it the ball bearing assembly 61 and the shaft 50. When the wheel is rotated in the opposite direction, it lowers the shaft 50. If the assembly thus provided

is lowered far enough, the grinding wheel 57 engages the top of the rail, as illustrated in Fig. 4. Any further rotation of the wheel 69 is then effective to permit the spring 80 to thrust the shaft 50 and the grinding wheel 57 yieldingly against the top of the rail. The user thus does not have to exert any downward pressure, but merely has to control the position of the parts by rotating the wheel 69.

10 The grinding assembly is driven by a motor generally indicated as 85, the details of which do not of themselves form part of the present invention. The motor is provided with any suitable motor shaft 86. Mounted on the shaft 86 15 is a frictional driving member 87, which may be of fiber or the like. The frictional member proper is secured as by bolts 88 to the flange 89 of a hub 90, the hub and flange being keyed, as at 91, to the shaft 86. Screw threaded at one end 20 on the hub 90 is a ring 92, provided with a socket 93, which receives a spring thrust ball 94, adapted to seat in either one of a pair of seats 95 in a ring 96, which is also keyed to the shaft 86, and which abuts against a shoulder 97 on the 25 shaft 86. It will be understood that the ring 92 may thus be employed as a species of takeup ring to compensate for wear of the frictional drive member 87, and the balls serve to prevent unintended rotation of the ring.

30 The engine 85 is mounted on a platform 100, which is supported on an inner tube 101, which penetrates blocks 102 secured upon the side frame members 3. An outer tube 103 is connected, as by plates 104, with the platform 100.

35 Welded or otherwise secured to the opposite edge of the platform 100 is an angle member 105, to which is welded a wedge block 106. 107 is a plate welded to the transverse frame members 6 and overlying the wedge block 106. Between the plate 107 and the wedge block 106 is a movable wedge 108, which is yieldingly urged to the right, referring to the position in which the parts are shown in Fig. 9, by a coil spring 109, the opposite end of which is secured to an ear 110 on one 40 of the side frame members 3. 111 is a guide pin welded to the angle 105 and extending upwardly through an aperture in the plate 107. A spring 112 surrounds the pin 111 and is compressed between the members 105 and 107. Thus, the 45 weight of the platform may be employed to hold the frictional driving element 87 in driving relationship against the frictional driving element 46, whereby the grinding shaft 50 is driven. The wedge 108 prevents dancing of the motor platform and thus dancing of the driven member 87, and creates a positive engagement between the opposed members 87 and 46. The platform 100 is held in proper alignment by bars 113 welded to the frame members 3.

60 While the grinder is generally balanced on a rail 1, and when in use is held in an erect position manually by the operator, it often becomes necessary to leave it at rest without taking it off the rail. In order to obtain this result, a vertically adjustable support in the form of a rod is provided, generally indicated at 150, and it is provided for convenience with a sharp lower end 151, and a top handle or crook 152. The rod 150 may be guided in a plurality of eyes 153, 154, which

65 may be in the form of bands welded to the vertical frame member 13. 155 is a plate welded or otherwise secured to the frame member 13 and provided with an upper notch 156, which may receive an outwardly extending ear or lug 157 on the rod 150. This lug is normally moved into 70 75

latching position as by the spring 158 secured to the opposite vertical frame member 13, as at 159. A second plate 160 may be adjustably mounted at a plurality of positions in relation to the members 155 and 13, as by studs 161, penetrating any of a plurality of apertures 162. Any suitable nuts 163 may be employed to hold it in position. The plate 160 is provided with a bottom adjusting notch 164 and an outward bottom extension 165 to serve as a downward limit for the movement of the lug 157. It will be understood that, by rotating the handle 152, the lug 157 may be disengaged from the upper slot 156 in the plate 155, and the rod 150 may then be bodily moved downwardly and again rotated, with the lug 157 penetrating the bottom notch 164 of the plate 160. In either position the lug is held in notch engaging position by the above mentioned spring 158.

The center of mass of the grinder as a whole is somewhat to the left of the rail, referring to the position of the parts shown in Fig. 3. Therefore, when the member 150 is adjusted to the dotted line position of Fig. 3 and the device is released, it will tilt to the left until the sharp point 151 engages the tie 2 or the road bed. Preferably it is dropped into engagement with the tie, and the sharp point, by sinking into the tie, prevents undesired longitudinal movement of the grinder.

It will be realized that, whereas a practical and operative device is described and illustrated, nevertheless many changes may be made in the size, shape, number and disposition of parts without departing from the spirit of the invention. It is therefore wished that the description and drawings be taken as in a broad sense illustrative or diagrammatic, rather than as a limitation to the precise showing.

The use and operation of my invention are as follows.

The single rail grinder herein described and shown is supported on a single rail of a track. It is sufficiently light to be operated by one man and may be moved longitudinally along the track to and from a point of use. It may readily be removed from the track to permit the passage of trains. The operator, when grinding, releases the grinder 11 to a rail engaging position by rotating the hand wheel 69. It will be understood that the grinding wheel 51 with its shaft 50 is urged downwardly only by the spring 80 in addition, of course, to the weight of the grinding member. This part of the mechanism is, therefore, free to rise if the grinding wheel should meet a high spot. In other words, the grinding wheel is floated on the rail in such fashion that it can accommodate itself to changes in contour or in height of the rail.

The drive is maintained between the beveled driving member 87 and the beveled or conic driven member 46. The weight of the engine and engine platform is employed to maintain an adequate frictional driving connection. Referring, for example, to Fig. 1, the engine platform with the engine on it rotates about the center generally indicated at 101. The weight of the power plant is supported by this horizontally axised tilting connection on the one hand, and by the driven member 46 on the other. The member 87 overlies the member 46 and an effective driving contact is thus obtained.

An important feature of the device is shown in Fig. 9. The wedge 108 is yieldingly urged to the right, referring to the position in which the parts are shown in Fig. 9, this wedge tends to

hold the platform and engine downwardly with the friction wheel 87 in continuous contact with the driven member 46. The wedge also obviates the tendency of the platform to chatter when the engine is running at high speed. Thus it prevents the intermittent relief of driving contact which would otherwise occur between the two friction wheels, and materially contributes to the efficiency of the driving connection.

What is claimed is:

1. In a rail grinder, a supporting frame tiltably and longitudinally moved and entirely supported on a single rail of a track, a grinder shaft mounted on said frame for rotation about a generally vertical axis, a motor mounted on said frame, a frictional driving connection between said motor and said shaft, including a frictional driven member driven by the motor, and a frictional driven member held against rotation in relation to said shaft, said shaft being axially movable in relation to said driven member, a grinding tool at the lower end of said shaft, means for normally supporting said grinding tool and shaft, with the grinding tool upwardly spaced from the top of the rail, manually operable means for moving said shaft and grinding tool downwardly toward the rail, and a platform on which said motor is mounted, said platform being movable in relation to the supporting frame, the frictional driving member associated with the motor and platform being gravitally held by the weight of the platform and motor in contact with the frictional driven member.

2. In combination, in a rail grinder, a support 35 mounted for tilting movement on the single rail of a track, a grinding tool and shaft therefor mounted for rotation on said support about a generally vertical axis aligned with the top of the rail, means for imparting axial movement to said

40 shaft and tool, and driving means for the shaft and tool including a frictional driven element located adjacent the bottom of the shaft and above the tool, and having an upwardly conic surface, and held against rotation in relation to the shaft and tool, the tool being axially movable in relation thereto, a drive shaft and means for driving it, and a frictional driving element mounted thereon and having a conic surface opposed to the conic surface of the driven member, and means for maintaining the two members in driving contact, including a platform on which said driving element and the means for driving it are mounted, said platform being movably mounted on the frame, the weight of said platform and the parts mounted thereon being effective to urge the frictional driving element downwardly against the frictional driven element.

3. In a track grinder, a supporting frame and means for supporting it on a single track rail for movement longitudinally along the rail and for transverse tilting movement in relation to the rail, a generally upright grinding shaft on said frame, the axis of which is normally fixed in relation to the frame, said grinding shaft having a grinding member at the lower end thereof, a platform pivotally mounted on the frame for rotation about a generally horizontal axis, motor means on said platform, a drive shaft extending from said motor means and away from the pivotal connection between platform and frame, a frictional drive member mounted for rotation with said drive shaft, a frictional driven member associated with said grinding shaft and adapted to underlie and engage said frictional drive member, the weight of the platform and motor means

being effective to hold said frictional drive member gravitally downwardly against said frictional driven member in effective driving contact therewith.

4. In a track grinder, a supporting frame and means for supporting it on a single track rail for movement longitudinally along the rail and for transverse tilting movement in relation to the rail, a generally upright grinding shaft on said frame, the axis of which is normally fixed in relation to the frame, said grinding shaft having a grinding member at the lower end thereof, a platform pivotally mounted on the frame for rotation about a generally horizontal axis, motor means on said platform, a drive shaft extending from said motor means and away from the pivotal connection between platform and frame, a frictional drive member mounted for rotation with said drive shaft, a frictional driven member associated with said grinding shaft and adapted to underlie and engage said frictional drive member, the weight of the platform and motor means being effective to hold said frictional drive member gravitally downwardly against said frictional driven member in effective driving contact therewith and means effective normally to urge said grinding member downwardly against the surface of the rail, said grinding shaft being axially movable in relation to the frictional driven member.

5. In a track grinder, a supporting frame and means for supporting it on a single track rail for movement longitudinally along the rail and for transverse tilting movement in relation to the rail, a generally upright grinding shaft on said frame, the axis of which is normally fixed in relation to the frame, said grinding shaft having a grinding member at the lower end thereof, a platform pivotally mounted on the frame for rotation about a generally horizontal axis, motor means on said platform, a drive shaft extending from said motor means and away from the pivotal connection between platform and frame, a frictional drive member mounted for rotation with said drive shaft, a frictional driven member associated with said grinding shaft and adapted to underlie and engage said frictional drive member, the weight of the platform and motor means being effective to hold said frictional drive member gravitally downwardly against said frictional driven member in effective driving contact therewith, and means effective normally to urge said grinding member downwardly against the surface of the rail, said grinding shaft being axially movable in relation to the frictional driven member, and means for varying said yielding thrust.

6. In a track grinder, a supporting frame and means for supporting it on a single track rail for movement longitudinally along the rail and for transverse tilting movement in relation to the rail, a generally upright grinding shaft on said frame, the axis of which is normally fixed in relation to the frame, said grinding shaft having a grinding member at the lower end thereof, a platform pivotally mounted on the frame for rotation about a generally horizontal axis, motor means on said platform, a drive shaft extending from said motor means and away from the pivotal connection between platform and frame, a frictional drive member mounted for rotation with said drive shaft, a frictional driven member associated with said grinding shaft and adapted to underlie and engage said frictional drive member, the weight of the platform and motor means being effective to hold said frictional drive member gravitally downwardly against said frictional

driven member in effective driving contact therewith, and means effective normally to urge said grinding member downwardly against the surface of the rail, said grinding shaft being axially movable in relation to the frictional driven member, and means for inhibiting said downward thrusting means and for holding said grinding member upwardly out of contact with the rail.

7. In a track grinder, a supporting frame and means for supporting it on a single track rail for movement longitudinally along the rail and for transverse tilting movement in relation to the rail, a generally upright grinding shaft on said frame, the axis of which is normally fixed in relation to the frame, said grinding shaft having a grinding member at the lower end thereof, a platform pivotally mounted on the frame for rotation about a generally horizontal axis, motor means on said platform, a drive shaft extending from said motor means and away from the pivotal connection between platform and frame, a frictional drive member mounted for rotation with said drive shaft, a frictional driven member associated with said grinding shaft and adapted to underlie and engage said frictional drive member, the weight of the platform and motor means being effective to hold said frictional drive member gravitally downwardly against said frictional driven member in effective driving contact therewith, and release means adapted to permit relative movement of the frictional driving member and the drive shaft in response to excess torque.

8. In a track grinder, a supporting frame and means for supporting it on a single track rail for movement longitudinally along the rail and for transverse tilting movement in relation to the rail, a generally upright grinding shaft on said frame, the axis of which is normally fixed in relation to the frame, said grinding shaft having a grinding member at the lower end thereof, a platform pivotally mounted on the frame for rotation about a generally horizontal axis, motor means on said platform, a drive shaft extending from said motor means and away from the pivotal connection between platform and frame, a frictional drive member mounted for rotation with said drive shaft, a frictional driven member associated with said grinding shaft and adapted to underlie and engage said frictional drive member, the weight of the platform and motor means being effective to hold said frictional drive member gravitally downwardly against said frictional driven member in effective driving contact therewith, and release means adapted to permit relative movement of the frictional driving member and the drive shaft in response to excess torque, and means for limiting the arc through which the platform can rotate.

9. In a track grinder, a supporting frame and means for movably supporting it on a rail, a grinding shaft and a grinding member thereon, and means for rotating said grinding shaft including a frictionally driven member movable in unison with said grinding shaft, a motor platform pivoted on said frame for rotation about a generally horizontal axis, a frictional driving member and a motor on said platform for rotating it, said driving member overlying and resting gravitally upon said frictional driven member, the weight of the platform and the motor being effective to maintain frictional contact between the driving and driven members and means for preventing chattering of said platform.

10. In a track grinder, a supporting frame and means for movably supporting it on a rail, a

grinding shaft and a grinding member thereon, and means for rotating said grinding shaft including a frictionally driven member movable in unison with said grinding shaft, a motor platform pivoted on said frame for rotation about a generally horizontal axis, a frictional driving member and a motor on said platform for rotating it, said driving member overlying and resting gravitally upon said frictional driven member, the weight of the platform and the motor being effective to maintain frictional contact between the driving and driven members and means for preventing chattering of said platform, including a wedge member interposed between said platform and said frame and yielding means for urging said wedge member into chatter preventing position.

11. In a track grinder, a supporting frame and means for movably supporting it on a rail, a grinding shaft and a grinding member thereon, and means for rotating said grinding shaft including a frictionally driven member movable in unison with said grinding shaft, a motor platform pivoted on said frame for rotation about a generally horizontal axis, a frictional driving member and a motor on said platform for rotating it, said driving member overlying and resting gravitally upon said frictional driven member, the weight of the platform and the motor being effective to maintain frictional contact between the driving and driven members and means for preventing chattering of said platform, including a wedge member interposed between said platform and said frame and yielding means for urging said wedge member into chatter preventing position, along a path generally parallel with the axis of said platform.

12. In a track grinder, a supporting frame and means for movably supporting it on a rail, a grinding shaft and a grinding member at the lower end thereof, and means for rotating said grinding shaft including a frictional driven member movable in unison with said grinding shaft and held against rotation in relation thereto, a motor pivoted on said frame for bodily rotation about a generally horizontal axis, said motor including a frictional driving member, said driving member overlying and resting gravitally upon said frictional driven member, the weight of the motor being effective to maintain frictional contact between the driving and the driven members, said grinding shaft being vertically movable in relation to said frictional driven members.

13. In a track grinder, a supporting frame and means for movably supporting it on a rail, a grinding shaft and a grinding member at the lower end thereof, and means for rotating said grinding shaft including a frictional driven member movable in unison with said grinding shaft and held against rotation in relation thereto, a motor pivoted on said frame for bodily rotation about a generally horizontal axis, said motor including a frictional driving member, said driving member overlying and resting gravitally upon said frictional driven member, the weight of the motor being effective to maintain frictional contact between the driving and the driven members, said grinding shaft being vertically movable in relation to said frictional driven members, the axis of rotation of said grinding shaft being generally vertically aligned with a rail upon which the supporting frame is supported, the axis of rotation of said frictional driving member being generally horizontal and being generally vertically aligned with and parallel with said rail.

14. In a track grinder, a supporting frame and means for movably supporting it on a rail, a grinding shaft and a grinding member at the lower end thereof, and means for rotating said grinding shaft including a frictional driven member movable in unison with said grinding shaft and held against rotation in relation thereto, a motor pivoted on said frame for bodily rotation about a generally horizontal axis, said motor including a frictional driving member, said driving member overlying and resting gravitally upon said frictional driven member, the weight of the motor being effective to maintain frictional contact between the driving and driven members, said grinding shaft being vertically movable in relation to said frictional driven members, means for holding said grinding shaft normally upwardly withdrawn from said rail and manually controllable means for urging said grinding shaft downwardly toward the rail.

15. In a track grinder, a supporting frame and means for movably supporting it on a rail, a grinding shaft and a grinding member at the lower end thereof, and means for rotating said grinding shaft including a frictional driven member movable in unison with said grinding shaft and held against rotation in relation thereto, a motor pivoted on said frame for bodily rotation about a general horizontal axis, said motor including a frictional driving member, said driving member overlying and resting gravitally upon said frictional driven member, the weight of the motor being effective to maintain frictional contact between the driving and the driven members, said grinding shaft being vertically movable in relation to said frictional driven members, yielding means tending normally to urge said grinding shaft downwardly toward said rail, means effective to inhibit said yielding means and to hold said grinding shaft withdrawn from said rail, and manually operable means for moving said inhibiting means downwardly toward the rail and for thereby permitting said yielding means to thrust said grinding shaft downwardly and to engage said grinding member yieldingly with the surface of the rail.

16. In a track grinder, a frame mounted on and tiltable in relation to a single track rail, a generally upright grinding shaft mounted for rotation on said frame, a limit member mounted for vertical movement on said frame adapted to limit the downward movement of the shaft and including a bearing connection with said shaft adapted to permit rotation of the shaft, yielding means tending normally to urge said shaft and grinding member downwardly toward and against the rail, manually controllable means for lowering said limit member through a range sufficient to permit said yielding means to thrust the grinding member into yielding contact with the surface of the rail, and means for rotating said grinding shaft including a motor and a driving connection between said grinding shaft and said motor effective throughout the range of vertical movement of the grinding shaft.

17. In a track grinder, a frame and means for movably supporting it on a track rail for longitudinal and transverse tilting movement in relation to the rail, a generally upright grinding shaft and a grinding member at the lower end thereof, a sleeve surrounding said shaft and means for holding sleeve and shaft against relative rotation while permitting said shaft to move longitudinally in relation to said sleeve, means for rotating said sleeve, limit means for raising

and lowering said shaft, including a limit member in which the upper end of said shaft is rotatably supported, and yielding means tending normally to urge said shaft and grinding member downwardly toward the track rail, said means being effective, when the limit member is moved downwardly a predetermined distance, to maintain a yielding downward thrust of said grinding member against the rail.

18. In a grinding assembly for track grinders, a frame and means for movably supporting it on a track rail, a sleeve mounted for rotation on said frame about a generally upright axis, a frictional driven member adjacent the lower end of said sleeve, a motor movably mounted on said frame, including a frictional drive member in gravitational engagement with said frictional driven member, a grinding shaft mounted for rotation within and in unison with said sleeve and connecting means therebetween adapted to permit longitudinal movement of shaft while holding it against rotary movement in relation to said sleeve, a limit member, located above the upper end of said sleeve and means for raising and lowering it, a bearing engagement between the upper end of said shaft and said limit member, adapted to permit rotation of said shaft in said limit member while limiting the downward movement of said shaft, and yielding means on said frame, adapted, when the limit member is moved downwardly a predetermined distance, yieldably to urge said shaft downwardly and thereby to maintain said grinding member yieldingly against said track rail.

19. In a track grinder, a supporting frame and means for movably supporting it on a rail, a grinding shaft and a grinding member at the lower end thereof, and means for rotating said grinding shaft including a frictional driven member movable in unison with said grinding shaft and held against rotation in relation thereto, a motor pivoted on said frame for bodily rotation about a generally horizontal axis, said motor including a frictional driving member, said driving member overlying and resting gravitally upon said frictional driven member, the weight of the motor being effective to maintain frictional contact between the driving and the driven members, said grinding shaft being vertically movable in relation to said frictional driven members, and means for preventing chattering of the motor in relation to the frame during operation of the drive.

20. In a track grinder, a supporting frame and means for movably supporting it on a rail, a grinding shaft and a grinding member at the lower end thereof, and means for rotating said grinding shaft including a frictional driven member movable in unison with said grinding shaft and held against rotation in relation thereto, a motor pivoted on said frame for bodily rotation about a generally horizontal axis, said motor including a frictional driving member, said driving member overlying and resting gravitally upon said frictional driven member, the weight of the motor being effective to maintain frictional contact between the driving and the driven members, said grinding shaft being vertically movable in relation to said frictional driven members, and

means for preventing chattering of the motor in relation to the frame during operation of the drive, including a wedge member interposed between said motor and said frame and yielding means for urging said wedge member into chatter preventing position.

21. In a track grinder, a supporting frame and means for movably supporting it on a rail, a grinding shaft and a grinding member at the lower end thereof, and means for rotating said grinding shaft including a frictional driven member movable in unison with said grinding shaft and held against rotation in relation thereto, a motor pivoted on said frame for bodily rotation about a generally horizontal axis, said motor including a frictional driving member, said driving member overlying and resting gravitally upon said frictional driven member, the weight of the motor being effective to maintain frictional contact between the driving and the driven members, said grinding shaft being vertically movable in relation to said frictional driven members, and means for preventing chattering of the motor in relation to the frame during operation of the drive, including a wedge member interposed between said motor and said frame and yielding means for urging said wedge member into chatter preventing position.

22. In a track grinder, a supporting frame, means for movably supporting it on a single rail of a track, including a pair of longitudinally aligned rollers mounted on said frame for rotation about parallel transverse axes, a grinding shaft mounted on said frame for rotation about an axis perpendicular to the axes of rotation of said rollers, means for driving it, said shaft being longitudinally movable, along its axis, in relation to said supporting frame and including a grinding member at its lower end adapted to engage the rail at an area between said supporting rollers, said supporting frame being adapted for ready transverse tilting in relation to the rail, and means for yieldingly urging said grinding member downwardly against the upper surface of the rail.

23. In a track grinder, a supporting frame, means for movably supporting it on a single rail of a track, including a pair of longitudinally aligned rollers mounted on said frame for rotation about parallel transverse axes, a grinding shaft mounted on said frame for rotation about an axis perpendicular to the axes of rotation of said rollers, said shaft being longitudinally movable, along its axis, in relation to said supporting frame and including a grinding member at its lower end adapted to engage the rail at an area between said supporting rollers, said supporting frame being adapted for ready transverse tilting in relation to the rail, and means for yieldingly urging said grinding member downwardly against the upper surface of the rail, including a power plant for rotating said shaft, said power plant being movably mounted on the frame, and a driving connection between said power plant and said shaft adapted to apply the weight of said power plant to the shaft.
